DOLL

Mildred Emma Kimberly, Tacoma, Wash.

Application January 14, 1958, Serial No. 49,253

Term of patent 14 years

(Cl. D34—4)

Fig. 1.

Fig. 2.

Fig. 3.

Fig. 1 is a front elevational view of a doll showing my new design;

Fig. 2 is an end elevational view thereof; and

Fig. 3 is a rear elevational view thereof.

I claim:

The ornamental design for a doll, substantially as shown.
